UNITED STATES PATENT OFFICE.

DEWEY L. HARRISON, OF FORT SMITH, ARKANSAS.

ELECTRIC SIGNAL-TRANSMITTING SWITCH.

Application filed August 7, 1926. Serial No. 127,908.

This invention relates to improvements in electric signal transmitting switches such, for example, as may be used for direction indicators for motor and other vehicles, and is 5 more particularly concerned with a switch structure by means of which the intended signal may be set in operation and kept in operation for a determined period whereupon it automatically is rendered inoperative.

10 Other objects and advantages will appear in the following specification, reference being had to the accompanying drawings, in which

Figure 1 is a sectional view of the improved 15 switch.

Figure 2 is a cross section taken on the line 2-2 of Figure 1.

Figure 3 is a cross section taken on the line 3-3 of Figure 1.

20 Figure 4 is a diagram of the electrical wiring.

Figure 5 is a side elevation of enough of an automobile illustrating the manner of mounting the switch on the steering post,

25 Figure 6 is an elevation of a direction indicator in connection with which the switch may be used.

Reference is made to Figures 1, 2 and 3 which illustrate the switch. It comprises any 30 suitable casing 1 which is evidently subject to considerable change in form and material because it cannot readily be determined what either of these may ultimately be. In practice the casing may be mounted in any conveniently accessible place, and for the purpose of illustrating its application to a direction indicator for motor vehicles, it is shown mounted upon the steering post 2 (Fig. 5) although, obviously, it may be mounted directly upon the steering wheel.

35 Slots 3, 4 and 5 (Fig. 1) permit the projection of the hook-ends of switch levers 6, 7 and 8 which are pivotally mounted at 9 within the casing and are provided for the 40 purpose of closing individual electrical circuits and for setting the timing mechanism of the switch in operation.

For the first purpose each switch lever has 45 a contactor 10, 11 and 12. These must be insulated from the switch levers, and this is preferably done by making the switch levers of insulating material. The various levers have associated contacts 13, 14; 15, 16; 17, 18 (Fig. 3), the first one of each pair being

shorter than the other. The longer contact 55 may remain in engagement with the lever contacts 10, etc. and it is not until the lever is moved down that engagement is made with both and an electrical circuit closed. The various contacts 13, 14, etc. are mounted 60 upon an insulating strip 19 which also has slots 20 for the passage of the levers.

For the second purpose the switch levers are joined by a connecting bar 21 having slots 22 receiving pins 23 of the levers. The bar has a notch 24 receiving the end of a spring trigger 25. This trigger is mounted at 26 upon the casing. It has a lug 27 entering a notch 28 in a disk 29. This disk is capable of being turned by any suitable spring clock-work, the illustration of which has been confined to the showing of a spring barrel 30 and suitable intermediate gearing 31, but which may be of any suitable standard form with suitable means for rewinding the spring such as the usual hand winding spindle with pawl and ratchet control. Depression of a switch lever will disengage the lug 27 permitting rotation of the disk 29 and keeping one of the three circuits involved closed until the notch 28 comes around into the original position whereupon the trigger 25 restores the depressed switch lever and opens the circuit.

Reference is now made to Figures 5 and 6. In Figure 6 the signalling device illustrated comprises the legend 31 reading "Stop" and the legends 32 and 33 which read "Turn," but being associated with left and right arrows 34 and 35. These form part of the casing 36 upon which the smaller casing 37 of the "Stop" legend is suitably mounted. The glass or lens 38 in the center of the casing 36 is preferably of green color. The casing 36 includes a bracket 39 by which the device is mounted upon a motor vehicle, for example the rear left fender.

The electrical wiring is illustrated in Figure 4. Signalling devices in the form of lamps 40, 41 and 42 provide for the illumination of the various legends 31, 32 and 33. A 100 battery B is the source of electric current. A wire 43 from one pole of the battery has branches 44, 45 and 46 to the various contacts 14 and 18. The complementary contacts 13, 15 and 17 have wires 47, 48 and 49 running to one side of the respective lamps 42, 40 and 41. The other sides of these lamps are connected with the other pole of the bat-

tery by a wire 50. The lamp 51 behind the green glass 38 will receive current over an independent circuit (not shown).

- The operation is readily understood. It has been explained that the switch casing 1 may be mounted in any convenient position, the showing of the mounting of the casing upon the steering post 2 in Figure 5 merely being illustrative of one manner of mounting.
- 10 It will be evident by a comparison of Figures 1 and 4 that the respective switch levers 6, 7 and 8 are identified with the right turn, stop and left turn signals which the device is capable of giving.

15 Assume that the driver desires to indicate a right turn. He gives the hook-end of the switch lever 6 (Fig. 4) a downward blow. This rocks the switch lever on its pivot 9 and depresses the connecting bar 21. The other levers are not disturbed by virtue of the slot connections. The downward blow is transferred to the spring trigger 25, the connection of one end of the trigger with the notch 24 being noted.

25 Disengagement of the lug 27 with the notch 28 in the disk 29 follows. The spring clock-work sets the disk 29 in rotation, and the lug 27 rides upon the periphery of the disk holding both the connecting bar 21 and the switch 30 lever 6 in the depressed position.

The engagement of the contacts 13 and 14 by the contact 10 upon the foregoing depression of the switch lever 6 lights the lamp 42 (Fig. 4) and indicates the desired right turn, 35 the circuit being as follows: battery B, wires 43 and 44, contacts 14, 10 and 13, wire 47, lamp 42 and wire 50 back to the battery. As soon as the notch 28 returns to registering position in respect to lug 27 the latter drops 40 in by virtue of the tension of the spring trigger 25, raising the connecting bar 21 and restoring the switch lever 6 to the original position thereby automatically opening the foregoing circuit. The clockwork gearing 45 may obviously be of any desired ratio so that the foregoing timing afforded by the disk 29 may be of any duration. The depression of the switch levers is manual, but the maintenance of the signal in operation is automatic, as is also the opening of the signal 50 circuit. To give an example, the gearing may be such that the lamp 42 will remain lighted approximately 20 seconds, this evidently being the time required for a complete revolution of the disk 29. An operation similar to the one described follows the depression of either of the remaining switch levers 7 and 8.

60 While the construction and arrangement of the improved switch is that of a generally preferred form, obviously modifications and changes may be made without departing from the spirit of the invention or the scope of the claims.

Obviously, the construction of the switch is independent of the particular signalling

system and either one or a plurality of switch levers may be selectively and simultaneously operated.

I claim:—

1. In an electric signal transmitting switch, 70
a circuit including a pair of spaced contacts,
a switch lever movable to and from circuit
closing position between and in engagement
with said contacts, and means including a motor
driven train of gearing and a control disk set in operation by movement of the lever
to circuit closing position and effective to
hold the lever thus for a predetermined
period and then move the lever to circuit
broken position. 75
80

2. In an electric signal transmitting switch, an electrical circuit including a pair of spaced contacts, a switch lever movable to and from circuit closing positions between and in engagement with the contacts, means including a motor driven control disk set in motion by movement of the lever to the circuit closing position and a disk engaging, lever-connected member for holding the lever thus and the circuit closed for a predetermined period, said member being operative at the expiration of said period to reversely move the lever from circuit closing position and to arrest movement of the disk.

3. An electric switch comprising a plurality of independently operable switch levers, each having associated therewith a pair of spaced contacts and means including a motor driven rotatable control member and a connection therefrom common to said plurality of levers for holding selected levers stationary in circuit closing position between said spaced contacts for a predetermined period, and for thereafter automatically moving said lever to open the circuit and arrest 100 rotation of said control member. 105

4. An electric switch comprising a plurality of independently operable switch levers with each lever having associated therewith a pair of spaced contacts in an electrical circuit between and in engagement with which it is movable, a power driven rotatable element having a peripheral depression, a spring pressed trigger having a lug normally tending to occupy the depression and arrest rotation of said element and riding on the periphery of said element when the latter is released and rotates, and a motion transmitting member common to said plurality of levers and connecting said levers with said trigger to displace its lug from said depression upon manually effected movement of a selected lever to circuit closing position, thereby permitting said rotatable element through the trigger and its connected motion-transmitting member to hold the selected lever stationary in circuit closing position until the lug again enters the depression, the trigger then through its spring acting through the motion transmitting member

automatically and reversely to move the lever to open circuit position.

5. A switch comprising a plurality of independently operable levers, a disk having a depression, means to rotate the disk, a spring trigger having a lug seated in the depression preventing rotation, a motion transmitting bar common to and having pin and slot connection with each of the levers permitting 10 movement of selected levers to a circuit clos-

ing position without disturbing the others, said bar having a notch therein to receive the trigger and operating, when moved by circuit closing movement of a selected lever to displace the lug and permit rotation of the disk, said lug riding on the periphery of the disk to hold said bar with said lever stationary in the circuit closing position until registration of the depression with the lug. 15
